DESIGN FOR A DETACHABLE SUPPORT FOR INSTRUMENTS AND CONTROL DEVICES

Frederick H. Drake, Boonton, and Atherton Noyes, Jr., Mountain Lakes, N. J., assignors to Aircraft Radio Corporation, Boonton, N. J., a corporation of New Jersey

Application January 16, 1941, Serial No. 98,132

Term of patent 14 years

To all whom it may concern:

Be it known that we, Frederick H. Drake and Atherton Noyes, Jr., citizens of the United States, residing at Boonton, county of Morris, State of New Jersey, and Mountain Lakes, county of Morris, State of New Jersey, have invented a new, original, and ornamental Design for a Detachable Support for Instruments and Control Devices, of which the following is a specification, reference being had to the accompanying drawing, forming part hereof, and wherein:

Fig. 1 is a perspective view of the detachable

support for instruments and control devices, showing our new design; and

Fig. 2 shows perspective views of the inner faces of the base plate and inner plate members of the detachable support.

We claim:

The ornamental design for a detachable support for instruments and control devices, as shown.

FREDERICK H. DRAKE.
